UNITED STATES PATENT OFFICE.

JOHN P. GALLAGHER, OF JERSEY CITY, NEW JERSEY, ASSIGNOR TO MAGOR CAR CORPORATION, OF NEW YORK, N. Y., A CORPORATION OF DELAWARE.

COMBINED DRAFT ARM AND CENTER SILL REINFORCEMENT.

Application filed October 18, 1922. Serial No. 595,461.

To all whom it may concern:

Be it known that I, JOHN P. GALLAGHER, a citizen of the United States, and resident of Jersey City, in the county of Hudson and State of New Jersey, have invented certain new and useful Improvements in Combined Draft Arm and Center Sill Reenforcements, of which the following is a specification.

The invention relates in general to an improved form of car center sill construction for use in connection with freight, passenger and other forms of cars, and the invention specifically relates to a metallic reenforcement for the center sills and related structural elements found on certain makes of freight cars now in general use and which have their center sills formed wholly or in part of wood.

The designers of wooden freight cars did not provide a sufficiently rigid structure to withstand the lading strains and the pulling and buffing shocks to which the underframes of modern steel cars are subjected at present. Attempts have been made heretofore to reinforce the old wooden car underframe construction so as to meet present service conditions usually by providing complicated and frequently unnecessarily massive fabricated structures formed from commercial shapes and crudely assembled with the result that the added material has not been advantageously utilized. This practice has added unnecessarily to the cost and in general has resulted in a rather make-shift construction which is neither neat in appearance nor economical in labor and material costs.

In this application, the invention has for certain objects the providing of a simplified form of reenforcement for wooden car underframes, which will feature a minimizing in the amount of material used as well as the cost necessary to fabricate the reenforcing structure, which will provide for the necessary adjustment to fit underframe constructions in which the elements are differently spaced; which will eliminate parts heretofore regarded as necessary in such constructions; which will reduce the amount of labor necessary to mount the reenforcement in position in the underframe and at the same time which will provide a type of reenforcement adequate to the requirements in such circumstances.

Incidental to the general object to provide for the minimizing of separated parts the disclosure has for an additional object the providing of a form of center sill reenforcement which includes as a part thereof certain extensions overlapping the car bolsters and designed to function as gusset plates and as diagonal strain braces. In the illustrated showing these extensions are integral with the sill reenforcements. In this way there is eliminated the necessity for using separate gusset plates, and incidentally there is eliminated the labor necessary to the installation of separate gusset plates.

Where attempts have been made in the prior art to reenforce the parts of the center sills between each end sills and the adjacent bolster, it has been usual to locate the reenforcement in the longitudinal center of the car and within the outlines of the center sills. The result of this construction when the car is in service is that shocks on the end sills are transferred to the central portion of the bolster with a resulting tendency of the bolsters to buckle at the center. The old construction also tends to localize shocks to the upper zone of the bolster, resulting in a tendency of the bolster to tip or cant, so that it not infrequently happens that the bolster is torn away from the other parts of the underframe construction.

Accordingly, another object of the invention is to provide, in connection with the center sill reenforcement feature, strain transmitting elements which will function as strain braces to distribute the centrally directed shocks on the end sills rearwardly and outwardly to the outside of the center sill construction and along a material length of the bolster. The invention further features an end construction which will distribute shocks towards the intermediate or side sills usual in wooden car underframe constructions and in this way utilize the intermediate sills as well as the side sills to distribute and absorb part of the buffing shocks.

It is suggested in the present disclosure that the center sill reenforcement be in one piece and continuous from end to end of the car. It is apparent however that the parts at each end of the car, and which constitute combined center sill reenforcements, draft arms diagonal braces and gusset

plate, will be relatively massive and of a size not conveniently handled by the usual forms of stamping or pressing machines.

Accordingly the invention herein disclosed features a three part of unit reenforcement which will comprise the combined units at each end of the car and which preferably will have a length to extend from the end sills past the adjacent bolsters, and a third unit of a length sufficient to connect the end units. This three unit construction has the advantage that standard parts can be readily cut to size to fit car underframes of varying lengths. This midsection may be omitted but is suggested for use both as a reenforcement connecting element as a center sill reenforcement in those situations where it is deemed advisable to reinforce the center sills at their midlengths.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Figure 1 is a plan view adjacent one end of a wooden car underframe equipped with a preferred embodiment of the invention and with parts broken away to show details of construction.

Figure 2 is a perspective view of one of the ends units forming part of the complete reenforcement partially shown in plan in Fig. 1.

Figure 3 is a longitudinal sectional view taken in the longitudinal medial plane of the car, on the line 3—3 of Figure 1 and looking in the direction indicated by the arrows; and

Figure 4 is a transverse sectional view adjacent the bolster taken on the line 4—4 of Figure 1 looking in the direction indicated by the arrows.

In the following description and in the claims, parts will be identified by specific names for convenience of expression but they are intended to be as generic in their application to similar parts as the art will permit.

In the drawings there is shown a wooden car underframe formed of longitudinally extending members comprising a pair of transversely spaced apart wooden center sills 10 and 11, side sills 12 and 13, and intermediate sills 14 and 15; and transversely extending members including one of the end sills 16 and the adjacent bolster 17. It is understood that the structure shown in Figure 1 is duplicated at the opposite end of the car. There is also disclosed in outline cer-

tain other structural features of the car, including a buffer block 18, guard plate 19 and one of a pair of draft sills 20 which draft sills underlap the center sills and extend from the bolster to the front of the guard plate as is usual in such constructions.

It is understood that this showing is intended to represent conventional structures and to disclose a type of wooden underframe which is to be reinforced by the metallic construction particularly forming the subject-matter of this application.

In the form herein illustrated the center sill reenforcement comprises three major and two minor units formed of metal plate pressings. Of the major pressings there is intended to be used two end members each extending from one of the end sills past the adjacent bolster and a connecting member disposed between the end members and fastened at each end to the end members by means of tie plates which constitute the two minor units and are preferably pressings.

Referring to either of the end members, 21 in Fig. 2, there is illustrated a single metal plate pressing having a length sufficient to extend from the end sill to the bolster and preferably across the bolster for a distance equal to or less than the distance from the bolster to the end sill. In the preferred form shown in Figure 1 the pressing is of a length to extend towards the center of the car from the bolster a distance approximately more than one-half of the distance between end sill and bolster. The central portion of the pressing is bent longitudinally into a channel 22, inverted U-shaped in cross-section and of a size to fit between the inner faces of the center sills and acting to form a thrust beam at the adjacent end of the car underframe. This beam includes a pair of vertically disposed webs 24, a top flange 25 and outstanding bottom flanges 26 which project integrally from the lower edges of each of the webs 24 and coact therewith to provide right angle seats for the wooden center sills 10 and 11. It is within the scope of the present disclosure to form this part of the beam of Z-shaped pressings with lapped flanges riveted together.

In the present instance the flanges 26 are extended on each side beyond the outer faces of the adjacent center sills to provide horizontally disposed plates 27. Each plate is of maximum width along the bolster, and in the form of the invention disclosed in Figure 1 extends to the adjacent intermediate sill 14 or 15. The plate is of gradually reduced width in both directions from the bolster and forms between the bolster and the adjacent end sill a triangular shaped plate 28 which coacts with the adjacent upstanding web 24 to form an angle pressing

which in addition to providing a seat for the wooden sill will function as a diagonal strain transmitting brace to distribute shocks received at the center of the end sill and to convey the same to the portions of the bolster to the outside of the center sills.

In another aspect of the disclosure it may be considered that the narrow flange 26 on each side of the center together with the portion 28 of the extension and without the web 24 will be of sufficient strength to constitute a strain brace. The general effect of the construction as thus far described will be to effect a transference and distribution of shocks at the center of the end sill in direct lines to the central portion of the bolster and along outwardly divergent lines to the portions of the bolster outside of the center sill construction. The portion of the flanges 28 which extend horizontally beyond the center sills are fastened to the bolster by means of rivets 29 and in this way there is provided a plate which functions as the usual gusset plate between the center sill construction and the bolster.

The central unit 30 connecting the end pressings 21 resembles the end pressings in outline and dimension, except that it is not provided with the gusset plate forming extensions 27. This part of the construction is simply a one-piece channel shaped member, preferably a pressing, inverted U-shaped in cross-section and provided with outstanding flanges 31. However, this part may obviously be formed of two Z members riveted together as is shown in the companion application above identified. The ends of the central pressing are secured to the adjacent end pressings by means of tie plates 32 which extend across the joints between the units and are fastened by rivets 33. In the present disclosure this tie plate corresponds in cross section to the central member, except that it is of corresponding smaller size so as to fit in the trough or channels of the members to which they are attached.

Where the question of economy in reinforcements is vital the central pressing may be reduced in the amount of material used; may have some of its parts omitted; or may be omitted entirely. In this latter case dependence is placed upon the unreinforced wooden center sills to provide the necessary structure parts at the center of the underframe.

The parts of the reinforcement are secured to the center sills by vertically disposed bolts 34 and horizontally disposed bolts 35 as more particularly suggested in the copending application. The end pressings may be secured to the end sills and in order to provide a broad bearing attachment the end of the top flange 25 is down-

turned to provide a depending transversely extending attaching web 36. This web abuts the inner side of the end sill between the center sills and is secured in place by bolts 37 which pass therethrough and 70 through the buffer block 18.

In operation it will be understood that there will be kept in stock a supply of the end and central units which will be standard for all car constructions of one type. In such 75 cars the distances between end sills will frequently vary but this variation may be compensated for by cutting the central member to proper length. The tie plates are riveted in place and the complete reenforcing structure thus fabricated is disposed in position in the car underframe.

By means of the device herein disclosed it is possible to distribute shocks received on either end sill constructions throughout the 85 major portion of the car underframe and in this way strengthen the construction as a whole in such manner that the reinforced car can be distributed in a train together with modern all-steel cars. 90

It is a feature of this construction that the usual multiplicity of parts have been reduced to the smallest possible number and there is eliminated the weakening effect of the usual multiplicity of bolt holes as well 95 as the elimination of the labor necessary to rivet the parts together. There is further effected a saving of material and in general there is provided a lighter, neater and less cumbersome structure than has heretofore 100 been regarded as necessary to effect the reinforcements of wooden car underframes.

While I have shown and described, and have pointed out in the annexed claims, certain novel features of my invention, it will 105 be understood that various omissions, substitutions and changes in the form and details of the device illustrated and in its operation may be made by those skilled in the art without departing from the spirit of the invention. 110

Having thus described my invention, I claim:

1. In a car underframe, the combination with an end sill, a bolster and a pair of center sills to be reinforced, of a pressing extending from the end sill past the bolster, a part of said pressing fitted between the center sills to form a thrust beam reenforcing the same, said pressing including on each side outwardly extending flanges integral with the beam and overlapping the bolster, the parts of said flanges between the bolster and center sills constituting gusset plates and the parts of the pressing between the 120 end sill and bolster constituting diagonal strain braces.

2. In a car underframe, the combination with a wooden frame including longitudinal center, intermediate and side sills and a 125

transverse end sill and bolster, of a single metal plate structural unit extending longitudinally from the end sill across the bolster, extending transversely at the bolster from one intermediate sill to the other, converging in horizontal width from the bolster towards the end sill and extending at the end sill from the outer side of one center sill to the outer side of the other center sill, 10 said unit including a channel shape central part fitted between the center sills to reenforce the same, and longitudinal edge portions extending integrally from said central portion for transferring strains outwardly 15 from the end sills to the portion of the bolster on opposite sides of the center sills.

3. In a car underframe, the combination with a wooden frame including longitudinal center, intermediate and side sills and a 20 transverse end sill and bolster, of a single metal plate structural unit extending longitudinally from the end sill across the bolster, extending transversely at the bolster from one intermediate sill to the other, converging in horizontal width from the bolster 25 towards the end sill and extending at the end sill from the outer side of one center sill to the outer side of the other center sill and means for securing said single unit to 30 the bolster and center sills.

4. In a car underframe construction, the combination with a bolster and one end sill, of a structural unit extending from the end sill past the bolster, overlapping and supported by the bolster, said unit including a vertically disposed web and a horizontal web integral with each other, the parts thereof between the end sill and the bolster constituting strain distributing braces and the 40 parts overlapping the bolster constituting gusset plates.

5. In a car underframe construction, the combination of an end sill, a bolster and a pair of center sills to be reenforced, of a re-enforcing unit shaped to provide center sill reenforcing elements extending across the bolster and fitted between the center sills and to provide strain distributing braces between the end sill and bolster. 50

6. In a car underframe construction, the combination of a bolster and a pair of center sills to be reenforced, of a reenforcing unit shaped to provide center sill reenforcing elements a spacing element extending between the sills and to provide gusset plates between the bolster and center sills on opposite sides of the center sills and on opposite sides of the bolster. 55

7. In a car underframe construction, the combination with a bolster and a pair of center sills to be reenforced, of a reenforcing unit including, on opposite sides of the medial longitudinal vertical plane of the car, an angle shape for reenforcing the adjacent center sill, and a part of said shape fitted to

extend horizontally between the sills and other parts extending from the sill reenforcing part in overlapped relation to the bolster to form a gusset plate extending longitudinally on opposite sides of the bolster. 70

8. In a car underframe construction, the combination with an end sill, a bolster and center sills to be reenforced along their entire length between the end sill and the bolster, of a sill reenforcing member, extending along each sill from the end sill to the bolster, said member including a channel shaped part disposed between and reenforcing the center sills, flanges extending outwardly therefrom on opposite sides of 80 the sills, the parts of said flanges between the end sill and bolster constituting strain distributing braces.

9. In a car underframe construction, the combination with a center sill to be reenforced and a bolster, of an angle shape including an upstanding element and a horizontal element integral therewith, means for securing both elements to the center sill to reenforce the same and the horizontal element extending beyond the center sill and in overlapped relation to the bolster to form a gusset plate integral with the center sill reenforcing part. 90

10. In a center sill construction, the combination of a pair of parallel wooden center sills, a metallic reinforcement therefore comprising a metal pressing shaped to provide an inverted U-shape beam disposed between the center sills and flanges converging in width from adjacent their centers towards opposite ends extending integrally from the U-shaped portion and underlapping the wooden sills. 95

11. A structural unit for car underframes comprising a central, inverted U-shaped center sill reenforcing part adapted to fit between the center sills to be reenforced and horizontally extending flanges projecting laterally from opposite sides of said central part, said flanges adapted to be secured to center sills and constituting combined diagonal strain braces and gusset plates for distributing buffing shocks along the car bolster to the outside of the center sills and for tying the bolster to the center sills in spaced relation to their adjacent ends. 110

12. A metal pressing for car underframes including a trough shaped central beam having vertical and horizontal webs, said horizontal webs having lateral extensions with a maximum width adjacent their mid-length and converging in width towards opposite ends. 115

13. A metal pressing for car underframes including a channel shaped central beam having a pair of vertical, transversely spaced webs and gusset plate forming flanges outstanding horizontally from opposite sides of the beam, and extending longi- 125

- itudinally across and projecting beyond opposite sides of the car bolster, and said gusset plate provided with bolt holes for receiving fastening means to secure the same to the car bolster. 5
14. A structural unit for car underframes comprising a metal pressing having a length sufficient to extend from a car end to the adjacent bolster, said pressing fashioned to provide a center sill reenforcing shape for reenforcing the portion of the center sill between the car end and the adjacent bolster and including outstanding flanges on opposite sides thereof, each flange converging in width towards opposite ends and constituting braces on opposite sides of the bolster for transferring strains from the adjacent car end to the bolster and also to the bolster from the central portion of the center sill 10 on the side of the bolster opposite the adjacent car end. 20
15. A structural unit for car underframes comprising a metal pressing fashioned to provide a center sill reenforcing shape and including outstanding flanges on opposite sides thereof having their maximum width adjacent their centers tapering off therefrom in both directions towards their end constituting gusset plates for securing the car bolster to the center sills said unit provided with bolt holes adjacent one end for engaging with a reinforcement and provided with bolt holes adjacent the center for securing the same to a bolster. 30
16. A structural unit for car underframes comprising a metal pressing including an angle shape constituting a brace arm adapted to transfer strains from the car end to the adjacent bolster and one flange of said angle extended to provide a gusset plate adapted to be secured to the car bolster and to extend lengthwise of the bolster on opposite sides of the bolster. 40
17. A reenforcement for wooden center sill constructions including a pressing of a uniform thickness, having a central part inverted U-shape in cross-section and having outstanding flanges projecting integrally from the lower edges of the U-shaped central part said flanges having a maximum width adjacent their mid-lengths and tapering therefrom towards opposite ends. 45
18. In a car underframe, the combination with an end sill a bolster and a pair of center sills extending from the end sill past the bolster, of a metal pressing having a part fashioned to fit between the center sills to reenforce the same on opposite sides of the bolster and a transverse web extending, integrally from the sill reenforcing part and extending between the sills and means for fastening the web to the end sill. 55
19. A structural unit for car underframes comprising a metal pressing including an inverted U-shaped part for reenforcing the car center sills and a flange integral with said U-shaped part at one end and confined within the longitudinally projected outlines of the U-shaped part for securing the pressing to the car end sill whereby the top of the metal pressing will be flat and free of projections and may be secured by means of its flange to an end sill which does not project above the side sills. 60
20. In a car underframe, the combination with a pair of wooden center sills to be reenforced, end sills and bolster, of a fabricated metallic reenforcement including similar end units, each constituting a combined brace, center sill reenforcement and gusset plate structure, a central unit constituting a center sill reenforcement and cut to size to extend between the units and means for securing the central unit to the end units. 75
21. A car underframe reenforcement formed of three major units comprising two similar end units, each constituting a combined brace, gusset plate and center sill reenforcement for the part of the center sills adjacent the contiguous bolster and a connecting central unit of less material than the end parts and constituting a reenforcement for the central part of the center sills. 80
22. A car underframe reenforcement including three major units disposed in alignment, each constituting a metal pressing inverted U-shape in cross-section and adapted collectively to form a center sill reenforcement, two of said units at opposite ends of the reenforcement being similar in shape and each provided with outstanding flanges constituting combined strain transmitting braces and gusset plates and the third unit extending between the end units. 95
23. In a car underframe, the combination with structural parts to be reenforced, of a reenforcing structure comprising five parts fabricated to form a metallic structure extending from end to end of the car, said parts comprising two similar pressings, one at each end of the car, a central pressing disposed between the end pressings and two similar pressings for connecting opposite ends of the central pressing with the adjacent end pressing, said pressings coacting to provide a thrust beam from end to end of the car, and said end pressings each providing draft arms between the adjacent car end and its contiguous bolster and each providing gusset plates for connection with the adjacent bolster. 100
24. In a car underframe, the combination with a pair of wooden center sills to be reenforced, end sills and bolsters, of a fabricated metallic reenforcement including similar end units each constituting a combined brace, center sill reenforcement and gusset plate structure, a central unit constituting a center sill reenforcement and cut to size to extend between the end units and tie plates. 125
- 65

at each end of the central unit for securing the end units to the central unit.

25. A car underframe reenforcement including three major units disposed in alignment, each constituting a metal pressing inverted U-shape in cross-section and adapted collectively to form a center sill reenforcement, two of said units at opposite ends of the reenforcement being similar in shape and each provided with outstanding flanges constituting combined braces and gusset

plates and the third unit extending between the end units, and a tie plate inverted U-shape in cross-section extending across the joint between one end of the third unit and the adjacent end unit and fitted in the troughs of said units. 15

Signed at New York city in the county of New York and State of New York this 16th day of October, A. D. 1922.

JOHN P. GALLAGHER.
